UNITED STATES PATENT OFFICE.

LOUIS ALEXANDRE CADORET, OF PAWTUCKET, RHODE ISLAND.

SHUTTLE THREADER AND THREAD TENSIONER.

Application filed May 5, 1928. Serial No. 275,386.

The invention relates to improvements in means for effecting automatic threading of shuttles, and for placing the requisite tension upon the thread.

5 One object of the invention is to provide an exceptionally simple and inexpensive, yet an efficient and reliable device for effecting automatic shuttle threading.

10 A further aim is to provide unique means which may vertically float to the necessary extent with the thread, and will at all times serve to place the desired tension upon said thread.

15 Yet another object is to provide a simple and inexpensive construction in which both the shuttle threading means and the thread tensioning means may be advantageously embodied.

20 With the foregoing in view, the invention resides in the novel subject matter herein-after described and claimed, description being accomplished by reference to the accompanying drawings.

25 Fig. 1 is a top plan view of a portion of a shuttle equipped with one form of the invention.

Fig. 2 is a longitudinal sectional view through the shuttle illustrating a side elevation of the threader and tensioner.

30 Fig. 3 is a vertical transverse sectional view on line 3—3 of Fig. 2.

Figs. 4 and 5 are perspective views of the threader and tensioner, looking in different directions.

35 Fig. 6 is a top plan view showing a modified form of construction.

Fig. 7 is a side elevation of the construction disclosed in Fig. 6.

Fig. 8 is a horizontal sectional view on line 40 8—8 of Fig. 7.

Fig. 9 is a top plan view showing a still further form of the invention.

Fig. 10 is a side elevation of the device shown in Fig. 9.

45 Fig. 11 is a horizontal sectional view on line 11—11 of Fig. 10.

All forms of the invention possess certain features in common, to which one description will be directed. Then, the differences in construction will be pointed out.

50 The number 12 denotes a base plate to be anchored in a shuttle recess. Rising rigidly from one longitudinal edge of this base plate, is a vertical wall 13, one end of which is directed laterally outward as at 14 and then obliquely inward as at 15. The lower edge

16 of the inwardly directed portion 15, declines from the terminal 17 of said portion 15, to the lower end of the corner 18 at which said portion 15 joins the portion 14. At this 60 lower end of the corner 18, an eye 19 is formed, the lower portion of said eye being open to admit a thread sliding down the edge 16 upon travel of the shuttle in the direction of the arrow A of Fig. 2. The 65 part 20 of the wall portion 15, between the edge 16 and the eye 19, is curved and constitutes a slender eye-guarding finger 20 preventing accidental throwing of the thread out of the eye. 70

Overlying the base plate 12, is a top plate 21, one longitudinal edge of which is joined to the upper edges of all of the wall portions 13—14—15, said top plate extending throughout the length of said edges. The 75 longitudinal edge of plate 21, opposite the wall 13, is curved downwardly and inwardly at 22, providing a hook formation to receive the thread when it is initially engaged with the threader, upon travel of the shuttle in 80 the direction A'. The first time the shuttle moves in this direction, the thread in unwinding from the filling, whips laterally and in so doing enters the hook 22. Then, when the shuttle is reversely driven along the lay, 85 in the direction of the arrow A, the free end of the thread slides down the edge 16, snaps past the finger 20 and enters the eye 19.

The device may be secured in the shuttle recess in any desired way, but I prefer to 90 form the wall 13 with an opening 23 to receive the conventional threader anchoring pin 24.

Extending between the portions of the plates 12—21, toward the filling, is a vertical pin 25 which is secured to at least one of said plates and preferably to both of them, this pin being usually passed through openings in said plates and upset. Slidable and rotatable upon this pin 25, are any desired 95 number of thread tensioning members 26 of any appropriate wear-resisting material, such as steel, glass, porcelain, etc. These members are free to both rotate and slide upon the pin 25 and they are so shaped that their 100 adjacent surfaces diverge outwardly to readily admit the thread between them, as shown most clearly in Figs. 2 and 3. During the operation of the shuttle, the tensioning members 26 are free to float vertically with the 110 thread and may also rotate, so that while they place no undue braking action upon the

thread, they maintain the requisite tension thereon. Moreover, rotation of the members 26, insures that any wear thereon shall be uniformly distributed, instead of taking place along a single line. Then too, attention is invited to the fact that the members 26 are duplicates as to size and shape, each being provided with an upper convex side and a lower convex side. Hence, when the adjacent thread-engaging faces of these members have become excessively worn by the thread, the other two faces of said members are still intact and may be presented toward each other for engagement with the thread, upon removal of the pin 25 and insertion of a new pin.

In Figs. 6, 7 and 8, an additional vertical pin 25^a is shown, disposed in the angle between the wall portions 14 and 15. The upper end of this pin is suitably anchored to the top plate 21, and upon said pin, I slidably and rotatably mount a thread tensioning member 26^a which places additional tension upon the thread as it travels through the eye 19.

If desired, instead of using the additional member 26^a, a pivoted thread-tensioning arm 26^b may be provided at the inner side of the wall 13, as shown in Figs. 9, 10 and 11, said arm being loosely pivoted so that while its weight places tension upon the thread, it may float to any extent, which may be necessary.

All forms of the invention are of exceptional simplicity, yet are efficient and in every way desirable. On account of the excellent results obtainable therefrom, the details disclosed are preferably followed. However, within the scope of the invention as claimed, variations may be made.

40 I claim:—

1. A shuttle threader comprising a base plate for anchorage in a shuttle recess, a vertical longitudinal wall rising from one edge of said base plate, one end portion of said wall being directed laterally outward for a short distance and then directed obliquely inward, and a horizontal top plate extending from the upper edge of said vertical wall and overlying said base plate, said top plate being joined to the upper edges of all portions of said vertical wall and extending to the terminal of said inwardly directed wall portion, said inwardly directed portion being declined from said terminal to the lower end of the corner at which it joins said outwardly directed portion, said corner having an eye open at its lower portion to admit thread sliding down said declined edge, the part of said inwardly directed portion between said declined edge and said eye constituting an eye-guarding finger.

2. A shuttle threader comprising a base plate for anchorage in a shuttle recess, a vertical longitudinal wall rising from one edge of said base plate, one end portion of said

wall being directed laterally outward for a short distance and then directed obliquely inward, and a horizontal top plate extending from the upper edge of said vertical wall and overlying said base plate, said top plate being joined to the upper edges of all portions of said vertical wall and extending to the terminal of said inwardly directed wall portion, the longitudinal edge of said top plate opposite said vertical wall being curved 70 downwardly and inwardly to receive the thread when initially engaged with the threader, said inwardly directed wall portion being declined from said terminal to the lower end of the corner at which it joins 80 said outwardly directed portion, said corner having an eye open at its lower portion to admit thread sliding down said declined edge, the part of said inwardly directed portion between said declined edge and said eye 85 constituting an eye-guarding finger.

3. A shuttle threader comprising a base plate for anchorage in a shuttle recess, a vertical longitudinal wall rising from one edge of said base plate, one end portion of 90 said wall being directed laterally outward for a short distance and then directed obliquely inward, and a horizontal top plate, extending from the upper edge of said vertical wall and overlying said base plate, said top plate being joined to the upper edge of all 95 portions of said vertical wall and extending to the terminal of said inwardly directed wall portion, the longitudinal edge of said top plate opposite said vertical wall being curved downwardly and inwardly to receive the thread when initially engaged with the threader, the end of said top plate opposite the aforesaid terminal being obliquely disposed in substantially the same direction as 100 said inwardly directed wall portion, said inwardly directed wall portion being declined from said terminal to the lower end of the corner at which it joins said outwardly directed portion, said corner having an eye 105 open at its lower portion to admit thread sliding down said declined edge, the part of said inwardly directed portion between said declined edge and said eye constituting an eye-guarding finger.

4. A shuttle threader and tensioner comprising a base plate, a top plate overlying said base plate, a vertical wall extending between longitudinal edges of said base and top plates, said vertical wall having a thread 110 guiding eye and an edge declined thereto, and thread tensioning means disposed between said base and top plates.

5. A shuttle threader and thread tensioner comprising a base plate, a top plate overlying said base plate, a vertical wall connecting said top and base plates, said vertical wall having a thread guiding eye and an edge declining to said eye, a vertical pin extending between said top and base plates and 125

secured to at least one thereof, and a thread tensioning member rotatable and slidable upon said pin.

6. A shuttle threader and thread tensioner comprising a base plate, a top plate overlying said base plate, a vertical wall connecting said top and base plates, one end of said vertical wall being directed first outwardly and then obliquely inward, the lower edge of said inwardly directed wall portion being declined from its terminal to the lower end of the corner at which it joins said outwardly directed wall portion, said lower end of said corner being formed with a thread-guiding eye, a vertical pin rigidly mounted within the angle between said outwardly and inwardly directed wall portions,

and a thread tensioning member rotatable and slidable upon said pin.

7. A structure as specified in claim 6; together with an additional pin inwardly spaced from the first named pin and rigidly mounted in a vertical position, and an additional thread tensioning member slidable and rotatable upon said additional pin. 20 25

8. In a thread tensioner, a pin, means for mounting said pin in a vertical position, and a pair of thread-tensioning members rotatable and slidable on said pin, said members being substantial duplicates and each having 30 smooth upper and lower convex surfaces.

In testimony whereof I have hereunto affixed my signature.

LOUIS ALEXANDRE CADORET.
